INVENTOR.
Don D. Myers
BY *Chester H. Braceletton*
ATTORNEY.

UNITED STATES PATENT OFFICE.

DON D. MYERS, OF TOLEDO, OHIO, ASSIGNOR TO INDUSTRIAL RESEARCH CORPORATION, OF TOLEDO, OHIO, A CORPORATION OF DELAWARE.

METHOD AND MACHINE FOR REFRIGERATION.

Application filed June 28, 1920. Serial No. 392,171.

To all whom it may concern:

Be it known that I, DON D. MYERS, a citizen of the United States, residing at Toledo, in the county of Lucas and State of Ohio, have invented certain new and useful Improvements in Methods and Machines for Refrigeration, of which I declare the following to be a full, clear, and exact description.

10 This invention relates to a method and means for refrigerating liquids, such as brines; or for cooling gases, such as air.

One object of the invention is to obtain the advantages possessed by the ordinary forms 15 of refrigerating systems without the use of pumps, valves, or circulating pipes required in the ordinary system employing the compression and expansion of gases.

Another object is to maintain the refrigerating gas hermetically sealed in containers 20 which have no communication with each other, thus avoiding leakage of gas such as frequently occurs in refrigerating systems of the prior art. Leakage of this gas may 25 result not only in the loss of the gas, but also in injury to life and property through the poisonous, obnoxious, or corrosive properties of the gas. In my invention, the container for the gas is free from any internal 30 mechanism thus making it unnecessary to open the container for any purpose whereby gases could be lost or cause injury.

A further object of the invention is to 35 provide a machine so simple in its operation and free from liability to get out of order that it may conveniently be used in private homes and establishments where skilled mechanics and repair men are not available.

Other objects, and objects relating to 40 details of construction and economies of manufacture, will appear as I proceed with the description of that embodiment of the invention, which for the purposes of the present application, I have illustrated in the accompanying drawings.

Fig. I is a vertical sectional view through one embodiment of my invention.

Fig. II is a vertical sectional view along the line II-II of Fig. I, looking in the direction indicated by arrows.

Fig. III is a vertical sectional view of another modification incorporating my invention.

Fig. IV is a vertical sectional view along

the line IV-IV of Fig. III, looking in the direction of the arrows.

In Figs. I and II, the casing 1 supports the rotary shaft 2, carrying the open ended drum 3, fixed thereto. A shaft 4, rigidly fixed in the casing, supports the wheel 5, upon the inclined portion 6. Radiating outward from the periphery of the wheel 5 are the arms 7 which cooperate with the arms 8, radiating from the closed end of the drum, to pivotally support collapsible chambers 9, which are filled with a fixed mass of ammonia, sulphur dioxid, or other suitable gas. The material of the chambers is chosen in view of its resiliency, and its resistance to the corrosive action of the gas used. At the outer end of the drum 3 are provided rectangular slots 10 through which the arms 7 of the wheel 5 project. Upon the shaft 2 is mounted the gear wheel 11, or other suitable power transmitting means which may be driven by a motor 12. Supported at the top of the casing is a blower 13 which supplies a current of cooling air, directed by a hood 14 upon each chamber as it passes through the upper part of the casing.

Adjacent to and parallel with drum 3, are supported the rotary drums 15, and 16, having ribs 17, projecting outwardly and fitting between adjacent chambers 9, as the drum 3 is rotated, thereby forming an effective sealing means to prevent an appreciable transfer of heat by gaseous flow in either direction between the upper and lower portions of the casing. In the base of the casing 1 is provided a reservoir 18 having suitable connections, such as that shown at 19, through which may be circulated the medium to be cooled, such as brine, air, or other fluid.

The operation of my invention shown in Figs. I and II, is as follows:

The motor 12, on rotating, turns the shaft 2 and the drum 3 thereby rotating the chambers 9 about the axis of the shaft 2. The inclined portion of the shaft 6 causes the chambers 9 to be compressed at the upper portion of the casing 1 and expanded at the lower portion of the casing. The slots 10 permit the arms 7 to reciprocate back and forth therein during each rotation, while the drum 3 drives the wheel 5, and maintains the arms 7 in line with the arms 8.

In compressing a chamber, as it travels from the bottom toward the top of the cas-

ing 1, the temperature of the chamber is elevated by the adiabatic compression of the gas therein, and as the chamber approaches the uppermost part of the casing, the heat arising from this increase of temperature is carried off by the cooling air directed by the hood 14 upon the chamber. As the drum 3 continues to rotate, the chamber passes out of the cooling current of air and the volume 10 of the chamber is sinusoidally increased, thereby causing an adiabatic expansion of the gas in the chamber and a consequent decrease in the temperature of the chamber. As the chamber approaches the lower portion 15 of the casing 1, it immerses in the brine 20, and the decreased temperature of the chamber causes it to absorb heat from the brine 20, thereby reducing the temperature of the brine. The chamber is then removed 20 from the brine, as the drum 3 rotates, and is sinusoidally compressed so that upon reaching the upper portion of the casing 1, it is again in a heated condition as described above in connection with the initial step in 25 the cycle of operations. This cycle is followed by a continuous series of similar cycles.

It is thus seen that the chamber is subjected to a sinusoidal change in volume, and 30 at the point of minimum volume in the cycle, the chamber is cooled by the cooling air; while at the point of maximum volume in the cycle, the chamber is heated by the brine, or in other words, reduces the temperature 35 of the brine. The portion of the cycle, corresponding to the interval of cooling of a single chamber 9, has a duration of less than one half a cycle of the drum; and similarly, the portion of the cycle, corresponding to 40 the interval of refrigerating of the brine 20 by a single chamber 9, is of less duration than one half a cycle of the drum 3. The point of minimum volume in the cycle occurs in the middle of the interval of cooling 45 of the chamber 9, while the point of maximum volume in the cycle occurs in the middle of the interval of cooling of the brine 20. By providing a plurality of chambers 9, uniformly distributed around the drum 3, 50 each passing over the same path and through the same cycle of volume change, it is possible to continuously withdraw heat from the brine, and thereby maintain the brine at a low temperature.

Referring to Figs. III and IV, a modification is shown in which the drum 21 is closed at both ends and provided with slots 22 through which the arms 23 of wheels 24 and 25 project to support chambers 9. Between 60 adjacent chambers 9 are provided separating ribs 26 which perform the function provided by the ribs 17 in the modification shown in Fig. II. The nozzles 27, 28 and 29 are so placed with relation to the recesses 65 30, formed between the ribs 26, as to furnish

an efficient supply of cooling air to the chambers while in the compressed condition. Aprons 31 and 32 cooperate with the ribs 26 to form a sealing means preventing transfer of heat by gaseous flow in either direction between the upper and lower portions of the casing.

The operation of the modification, shown in Figs. III and IV, is similar to that described in connection with Figs. I and II, the cycle of volume change of chambers 9 being sinusoidal, and the cooling of the chambers and of the brine occurring in the same relation as described above.

I am aware that the particular embodiment of my invention above described, and illustrated in the accompanying drawings, is susceptible of considerable variation without departing from the spirit thereof, and therefore, I desire to claim my invention broadly as well as specifically as indicated by the appended claims.

I claim as my invention:

1. The method of refrigerating, which consists in cyclically varying the volume of a fixed mass of gas, immersing said gas in a cooling medium during the half cycle nearest the minimum volume point in the cycle, and immersing said gas in a medium to be cooled during the other half cycle, whereby heat from said medium to be cooled is absorbed by the gas during said other half cycle.

2. The method of refrigerating, which consists in sinusoidally varying the volume of a fixed mass of gas, immersing said gas in a cooling medium during the half cycle nearest the minimum volume point in the cycle, and immersing said gas in a medium to be cooled during the other half cycle, whereby heat from said medium to be cooled is absorbed by the gas during said other half cycle.

3. The method of refrigerating, which consists in cyclically varying the volume of a fixed mass of gas, immersing said gas in a cooling medium during the half cycle nearest the minimum volume point in the cycle for a portion only of said half cycle nearest to said minimum volume point, and immersing said gas in a medium to be cooled during the other half cycle for a portion only of said half cycle nearest the maximum volume point, whereby heat from said medium to be cooled is absorbed by the gas during said other half cycle.

4. The method of refrigerating, which consists in sinusoidally varying the volume of a fixed mass of gas, immersing said gas in a cooling medium during the half cycle nearest the minimum volume point in the cycle for a portion only of said half cycle nearest to said minimum volume point, and immersing said gas in a medium to be cooled during the other half cycle for a portion

only of said half cycle nearest the maximum volume point whereby heat from said medium to be cooled is absorbed by the gas during said other half cycle.

5. The method of refrigerating, which consists in varying the volume of a fixed mass of gas periodically in accordance with a fixed cycle, immersing said gas in a cooling medium during the half cycle nearest 10 the minimum volume point in the cycle, and immersing said gas in a medium to be cooled during the other half cycle, whereby heat from said medium to be cooled is absorbed by the gas during said other half 15 cycle.

6. The method of refrigerating, which consists in periodically carrying out the following cycle of operations upon a fixed mass of gas in the sequence named: first, 20 adiabatically compressing the gas; second, immersing said gas while compressed in a cooling medium; third, adiabatically expanding said gas; fourth, immersing said gas while expanded in the medium to be 25 cooled.

7. The method of refrigerating by a series of sealed collapsible chambers filled with gas, which consists in serially compressing said chambers, passing them while compressed through a cooling medium, expanding them, and finally passing them while expanded through a medium to be cooled.

8. The method of refrigerating by an endless series of sealed collapsible chambers 30 filled with gas, which consists in translating the entire series in seriatim along a fixed path, compressing each chamber as it passes over a first portion of the path; cooling each chamber, while compressed, as it passes over 40 a second portion of the path; expanding each chamber as it passes over a third portion of the path; and immersing each chamber, while expanded, in the medium to be cooled, as it passes over a fourth portion 45 of the path.

9. The method of refrigerating by a plurality of sealed gas filled chambers, which consists in periodically repeating a cycle composed of the following operations performed in the order named: compressing the chambers progressively while translating them through a thermally neutral medium; then translating the chambers progressively, while compressed, through a cooling medium to reduce the temperature of the chambers; expanding the chambers progressively while translating them through a thermally neutral medium; and translating the chambers progressively while expanded through the medium to be cooled.

10. In a refrigerating machine, a rotary carrier, a chamber containing a constant mass of gas, supported at the periphery of said carrier, means for varying the volume 65 of said chamber as it moves with the car-

rier, said chamber transferring heat between angularly displaced points adjacent the periphery of said carrier.

11. In a refrigerating machine, a casing, a reservoir therein containing a medium 70 to be cooled, and a space in said casing containing a cooling medium, and rotary means supported in said casing for transferring heat from said medium to be cooled to said cooling medium, said means including a plurality of collapsible non-communicating gas filled chambers. 75

12. In a refrigerating machine, a casing, a reservoir therein containing a medium 80 to be cooled, and a space in said casing containing a cooling medium, and rotary means supported in said casing for transferring heat from said medium to be cooled to said cooling medium, said means including a plurality of non-communicating gas 85 filled chambers, and shielding means co-operating with said rotary means to prevent flow of gas between said reservoir and said space.

13. In a refrigerating machine, a cooling 90 medium and a medium to be cooled, a plurality of sealed collapsible gas filled chambers, and means for cyclically varying the volume of said chambers and simultaneously rotating said members to immerse said chambers in a cooling medium while said chambers are compressed, and to immerse said chambers in a medium to be cooled while said chambers are expanded. 95

14. In a refrigerating machine, an approximately cylindrical casing, a cup shaped drum, pivoted on its axis of revolution co-axial with said casing, having a plurality of rectangular slots at the rim of the cup, and a plurality of radial projections at the base of the cup, said projections having sockets in their ends, a fixed shaft inclined to, but intersecting the axis of said casing, a wheel pivoted upon said shaft, having radial projections at its periphery extending through and free to move in said slots, said projections having sockets in their ends and gas filled chambers having terminals at each end journaled in said sockets, whereby said chambers are supported substantially parallel to the axis of said casing, means for rotating said drum whereby said chambers are rotated and alternately compressed and expanded, a fluid medium in the lower portion of said casing to be cooled by said chambers coming in contact therewith, and a fluid medium in the upper portion of said casing for cooling said chambers. 100 105 110 115 120

15. In a refrigerating machine, a cylindrical casing, a cup shaped drum, pivoted on its axis of revolution co-axial with said casing, having a plurality of rectangular slots at the rim of the cup, and a plurality of radial projections at the base of the cup, said projections having sockets in their ends, 125 130

- a fixed shaft inclined to, but intersecting the axis of said casing, a wheel pivoted upon said shaft, having radial projections at its periphery extending through and free to move in said slots, said projections having sockets in their ends, and gas filled chambers having terminals at each end journaled in said sockets, whereby said chambers are supported substantially parallel to the axis of said casing, means for rotating said drum whereby said chambers are rotated and alternately compressed and expanded, a fluid medium in the lower portion of said casing to be cooled by said chambers coming into contact therewith, and a fluid medium in the upper portion of said casing for cooling said chambers, a rotary drum on each side of the upper portion of said casing parallel to said casing and having projecting ribs closely meshing with the chambers on said drum for preventing a flow of gas between the upper and lower portions of said casing.
16. In a refrigerating machine, a rotary drum having a plurality of recesses uniformly distributed around its periphery parallel to the axis of the drum, slots in said recesses, two wheels mounted at an inclination to each other in said drum, having arms extending through said slots, gas filled chambers supported in said recesses upon said arms, a casing surrounding the lower portion of said drum and pivotally supporting said drum, a reservoir in the base of said casing for containing a medium to be cooled, air cooling means supported above said drum, including nozzles directed upon said chambers, means to rotate said wheels whereby said containers are compressed and expanded, said chambers being cooled by the currents of air from said nozzles while said chambers are compressed and heated by said medium to be cooled while said chambers are expanded.
17. In a refrigerating machine, a rotary drum having a plurality of recesses uniformly distributed around its periphery parallel to the axis of the drum, slots in said recesses, two wheels mounted at an inclination to each other in said drum, having arms extending through said slots, gas filled chambers supported in said recesses upon said arms, a casing surrounding the lower portion of said drum and pivotally supporting said drum, a reservoir in the base of said casing for containing a medium to be cooled, air cooling means supported above said drum, including nozzles directed upon said chambers, means to rotate said wheels whereby said containers are compressed and expanded, said chambers being cooled by the currents of air from said nozzles while said chambers are compressed, and heated by said medium to be cooled while said chambers are expanded, and shielding means at the top of said casing for preventing a flow of gas to or from said reservoir.

In testimony whereof, I affix my signature.

DON D. MYERS.
